UNITED STATES PATENT OFFICE.

MARION C. D. FLEMING, OF FARMERSVILLE, TEXAS.

COLLAPSIBLE CHICKEN COOP.

Application filed July 12, 1926. Serial No. 121,972.

The present invention relates to improvements in chicken coops and has for its principal object to provide one which is of such construction as to permit the same to be compactly folded for shipping or storing purposes, the same being further adapted to be readily and easily set up in position for use.

Another important object of the invention is to provide a collapsible chicken coop of the above mentioned character wherein the same includes a bottom, foldable sides and ends, and a separate top, cooperative means being associated with the top and the bottom for securing the parts in their folded or collapsed position, additional means being provided whereby the top will maintain the sides and ends in an upright coop forming position.

A further object of the invention is to provide a collapsible chicken coop of the above mentioned character which is simple in construction, inexpensive, strong and durable and further well adapted to the purpose for which it is designed.

Other objects and advantages of the invention will become apparent during the course of the following description taken in connection with the accompanying drawings.

In the accompanying drawings forming a part of this application and in which like numerals indicated like parts throughout the several views:

Figure 1 is a perspective view of the collapsible chicken coop embodying my invention, the top being shown removed and illustrating the ends and sides in their coop forming position.

Figure 2 is an end elevation of the assembled coop, and

Figure 3 is an end elevation of the coop in its folded or collapsed position.

In the drawing wherein for the purpose of illustration is shown the preferred embodiment of my invention, the numeral 1 designates generally my improved collapsible chicken coop, the same comprising the substantially rectangular solid base or bottom 2 which is formed of wood. Suitable reinforcing strips 3 extend transversely across the under side of the bottom or base 2. A pair of upstanding bars 4 and 5 are secured to the respective longitudinal side edges of the bottom 2 and the upper portions of these bars extend above the upper surface of the bot-

tom or base 2 in the manner as clearly illustrated in Figure 2.

The coop further includes the end members 6 and 7 respectively, each of these end members includes a plurality of vertically spaced bars 8 and extending transversely across these bars and arranged in parallel spaced relation are the strips 9. The end members 6 and 7 are hingedly supported on the respective ends of the base or bottom 2, as illustrated at 10, and when these end members are folded inwardly, the same will rest on the upper face of the bottom 2 and will be disposed between the upper portions of the upstanding bars 4 and 5 which are secured to the longitudinal side edges of the bottom.

The side members forming a part of the coop are designated by the numerals 11 and 12 respectively and each of the sides is also formed of a plurality of vertically spaced bars 13 similar to the bars 8 and extending transversely across the bars 13 and arranged in parallel spaced relation are the strips 14. The side 11 is hingedly secured at its lower edge to the upper edge of the side bar 4 while the lower edge of the other side 12 is hingedly secured to the upper edge of the side bar 5 as is shown at 15 and 16, respectively. When the side members are folded inwardly, the same will be disposed directly above the infolded end members and will be disposed in the manner shown more clearly in Figure 3.

The coop further includes the top or cover denoted generally by the numeral 17 and the same comprises the spaced bars 18 and extending transversely across these bars and arranged in parallel spaced relation are the strips 19. The bars and strips which form the top as well as the sides and ends of the coop are formed of wood. An opening 20 is provided in the top 17 to permit access to the interior of the coop when the top is secured on the coop and this opening is normally closed through the medium of the hinged door 21, the door being hinged at its inner end to the intermediate bar at 22, co-operating spring pressed latches 23 being associated with the outer end of the door and the adjacent bar of the top in the manner clearly shown in Figure 1 for holding the door in a locked position.

A pair of strap irons 24 are secured at their inner ends on the top of the end bars 110

of the cover or top 17. The outer end portions of these strap irons are disposed downwardly as at 25 and terminate in the laterally projecting tongues 26 in the manner clearly shown in Figure 1, and the purpose thereof will be hereinafter more fully described.

Additional strap irons 27 at the sides of the top and the end portions of these strap irons are disposed downwardly as at 28. A clip like member 29 is carried by the under side of the top 17 at the intermediate portion of each of the side edges of the top.

In assembling the coop, the sides and ends are swung upwardly to the position shown in Figure 1 so as to form a rectangular shaped coop and the top 17 is then placed on the upper edges of the sides and ends so that the depending portions 28 of the strap irons 27 would engage the uppermost strip 14 of the sides 11 and 12 on the outer side faces thereof and the intermediate clips 29 will fit over the intermediate portion of the respective uppermost strip 14. The depending portions 25 of the strap irons 24 will be disposed adjacent the outer side of the uppermost strips of the end members 6 and 7 respectively, and adapted for cooperation with the laterally projecting tongues 26 are the pivoted locking bails or latches 30 which are carried by the end members 6 and 7. In this manner, the top 17 will rigidly secure and support the hinged end members and sides in an upright position so that the coop will be properly assembled and ready for use, and the strap irons will prevent the accidental collapsing of the coop.

When the coop is not in use, or whenever it is desired to fold or otherwise collapse the same in a compact manner, the latches 30 are disengaged from engagement with the laterally projecting tongues 26 and the top 17 is then lifted upwardly so as to be entirely removed from engagement with the ends and sides. The end members 6 and 7 are then folded inwardly so as to swing downwardly and lie flat against the upper surface of the base or bottom 2 of the coop. The side members 11 and 12 are then swung inwardly so as to also lie flat, and the same will be disposed over the infolded end members in the manner clearly shown in Figure 3. The cover 17 is then placed on top of the infolded side members and for the purpose of holding the parts of the coop in their folded or collapsed position, I provide a pair of lugs 31 which project outwardly from one side of the top, the same being adapted for engagement with the apertured strap irons 32 which extend upwardly from the adjacent side bar 4 and the manner in which these lugs cooperate with the strap

irons 32 is more clearly shown in Figure 3. A similar strap iron 33 extends upwardly from the other side bar and a spring urged latch 34 which is carried by the other side portion of the top is adapted for engagement with the aperture formed in the upper portion of the strap iron 33. The latch or bolt 34 may be retracted so as to be disengaged from the strap iron 33 through the medium of the handle 35 associated with the latch or bolt.

When the parts are arranged in the manner shown in Figure 3, a compact arrangement is afforded so as to permit the coop to be easily and readily handled or transported without occupying any considerable amount of space.

The simplicity in which my improved chicken coop is constructed enables the same to be readily and easily assembled or disassembled.

While I have shown the preferred embodiment of my invention it is to be understood that minor changes in the size, shape, and arrangement of parts may be resorted to without departing from the spirit of the invention and the scope of the appended claim.

Having thus described the invention, what I claim as new and desire to secure by Letters Patent is:—

A collapsible chicken coop comprising a bottom, side and end members hingedly secured at their lower edges to the bottom, and a separable top adapted to rest on the upper edges of the side and end members when the latter are disposed in coop forming relation, cooperating means between the top and the side and end members for holding the coop in its assembled position, said means comprising strap irons secured to the upper side of the top, the outer end portions thereof being disposed downwardly for engagement with the outer faces of the respective side and end members, a substantially inverted U-shaped spring clip secured to the underside of the top at the intermediate portion of each side edge thereof, said spring clips adapted to engage over the upper edges of the respective side members, the arms of each clip adapted to engage the outer and inner faces of the respective side members, and latching means associated with certain of said strap irons for locking the top and the coop in an assembled position, said latching means comprising laterally projecting tongues formed on the depending portion of the end strap irons, and pivoted bails secured on the end members and adapted for engagement with said tongues.

In testimony whereof I affix my signature
MARION C. D. FLEMING.
